TROLLEY WIRE SUPPORT

Albert H. Genter, Ross Township, Allegheny County, Pa., assignor to Duquesne Mine Supply Company, Pittsburgh, Pa., a corporation of Pennsylvania

Application November 22, 1938, Serial No. 241,796

4 Claims. (Cl. 191—38)

This invention relates generally to trolley wire equipment and more particularly to wire supports for connecting adjacent ends of trolley wires and for supporting trolley wires at intersections.

The principal object of this invention is the provision of a smooth continuous surface between a trolley wire and its support.

Another object is the provision of a trolley wire frog having a smooth and uninterrupted contacting surface between the wire and the frog.

Another object is the provision of improved clamping means for attaching a trolley wire frog to the adjacent ends of trolley wires.

Another object is the provision of a wedge clamping action for a trolley wire support.

Other objects and advantages appear in the following description and claims.

20 In the accompanying drawing a practical embodiment illustrating the principles of this invention is shown wherein:

Fig. 1 is a vertical section taken through a trolley frog comprising this invention.

25 Fig. 2 is a plan view of the under or contact engaging surface of the trolley frog shown in Fig. 1.

Fig. 3 is a vertical section taken on the line 3—3 of Fig. 2.

30 Fig. 4 is an enlarged side elevation illustrating one section of a trolley wire splicing clamp comprising this invention.

Fig. 5 is a sectional view of the clamp taken on the line 5—5 of Fig. 4.

35 Referring to the drawing, 10 represents the frog casting made up of the ceiling plate 11 with the depending track or current collector engaging portions 12, 13 and 14 and the depending guide flanges 15 along the marginal sides. The

40 ends of the ceiling slope upwardly as indicated at 16 and the ends of the guiding flanges flare outwardly as shown at 17 for receiving and guiding the spaced flanges of the trolley pulley or shoe through the frog. Ears 18 having vertically

45 disposed openings are provided on the sides of the frog casting for supporting or properly aligning the same in the trolley system.

Adjacent to the outer ends of the track sections 12, 13 and 14 a half clamping section 20 is formed integral with the frog casting. The top of the inner face of these sections intersects the center line of its respective track as indicated at 21 and the bottom is spaced therefrom to maintain the center of the trolley wire 22 in axial alignment with the center of the respective track.

The bottom edge 23 of these clamping sections is above the lowermost edge of the track and is provided with the longitudinal groove 24 for receiving a portion of the wire. Each of these clamping sections is provided with a complementary removable clamping jaw 25 which is provided with a corresponding groove 24 and a hole for receiving the clamping bolt 26 which secures the trolley wire in the channel formed by the oppositely disposed grooves.

Teeth 27 similar to that of a thread are formed in the surface of the grooves 24 and on the lip of the lower edge 23 for gripping the wire and holding it suspended. Figure eight or grooved trolley wire are best suited for being gripped and supported by this character of clamp. However almost any kind of wire may be employed. Thus the collector contacting surface of the trolley wire, when clamped in place on the ends of the frog casting, abuts against and is flush with the depending portions 12, 13 and 14. This smooth contacting surface eliminates a bump and permits the collector to ride smoothly off the wire onto the frog without arcing. The wire and the adjacent collector engaging portions of the frog do not become burned due to arcing caused by the collector striking an abrupt change in the contacting surface which momentarily separates it from contact.

The inner surfaces of the clamping sections 20 and 25 are provided with vertically disposed open slots 28 and horizontally disposed inclined grooves 29 above the inner end of the grooves 24 forming a throat for receiving a wedge 30. The wedge is dropped through the opening formed by the slots 28 in the clamping members and then forced into the tapered throat. The smooth surface of the top of the wedge engages the smooth tapered surfaces 29 of each section of the clamping members and since the wedge is narrower than the grooves 29 it does not have the tendency of separating the clamping jaws.

This wedge action forces the trolley wire against the teeth 27 in the grooves 24, thus tightly gripping the same. The wedge is provided with the teeth 31 which bite into the top surface of the wire and aid in holding it against slipping. The depending portions 12, 13 and 14 are partially hollowed out as indicated by the dotted line 32 of Fig. 1 and as shown in Fig. 3. Thus it is a simple matter to employ a rod and a hammer for driving the wedges into position.

The enlarged view of a trolley wire splicing clamp is shown in Figs. 4 and 5 which illustrates the application of this wedge for aiding in grip-

ping the adjacent abutting ends of two trolley wire sections without an intermediate section such as required in a frog. This splicer is made up of two clamping jaw members 33 and 34 having spaced clamping portions 35 connected at their lower ends by the intermediate clamping portion 36. The full section of each jaw member is provided with a groove 24 adjacent the lower edge 23 thereof for receiving the abutting ends of the adjacent trolley wire sections 22 when held in assembled relation by the clamping bolts 26. These grooves are similarly provided with the teeth 27 which are formed around the lip bounding groove and are disposed at a slight angle to the vertical but in opposite directions on each side of the center of the clamp as illustrated. This slanting of the teeth tends to force the wire 22 upwardly against the clamping action of the bolts when subjected to tensional stresses. The intermediate clamping portions 36 are provided with the vertical slots 28 and the horizontally disposed inclined grooves 29 are formed in the end clamping sections for receiving the wedges 30.

The clamping ends of the jaw member 33 of the splicer are connected at their upper ends by means of the bar 37 which is integral therewith and is offset to position the longitudinal axis of the bar in the plane of the axis of the trolley wire. A clamp or other means of support may be fastened to this bar for suspending the splicer to hold the trolley wire at its proper elevation.

Thus the slanting teeth in the grooves 24 of each of these trolley wire supports tend to move the wire up when subjected to tensional forces and the wedge 30 forces the wire downwardly against this action. Both members have teeth which bite into the wire, gripping it tightly and preventing it from being pulled out. This character of grip also provides a very low resistance contact for efficiently conducting an electrical current therethrough.

The wedging action produced by the teeth in the clamping grooves 24 of these supports combined with the opposed action of the tooth wedges 30 may be applied to other apparatus used to support a trolley wire, such as section switches, cross-overs etc., for tightly suspending the wire in position. However in each instance a smooth under-riding surface for the current collector is provided.

I claim:

1. In a trolley wire structure, the combination of a casting, means integral with the casting for securing the latter to a support, integral jaw members on the ends of the casting, a groove in the lateral face of said jaw members adjacent the lower edge thereof, clamping jaw members complementary to the jaw members of the casting and having corresponding grooves coacting to receive the upper portion of adjacent end portions of trolley wires, teeth in said grooves, the corresponding jaw members contacting at their upper ends to provide a fulcrum and registering holes in the jaw members below the fulcrums to receive clamping bolts, opposed upwardly open slots on the inner faces of the corresponding jaw members, an inclined seat connecting each slot with its corresponding groove, and wedges intro-

duced through said slots and driven against the corresponding seats of each jaw member into the coacting grooves to force the wires into engagement with the teeth.

2. In a frog structure for overhead conductors, the combination of an intermediate ceiling portion provided with track ribs on its under surface, integral jaw extensions of said intermediate portion corresponding to a half part of the track ribs and having longitudinal grooves on their lateral faces and upwardly extending ears, and complementary jaw members arranged to coact with said extensions to clamp the ends of the conductors in place, said complementary jaw members being provided with grooves complementary to the groove on said extensions for receiving the conductors therebetween, teeth in said grooves for grasping the conductors, upwardly extending ears on said jaw members mating with the ears of the extensions to form fulcrums, means below the fulcrums defining registering holes in the mating ears to receive clamping bolts, wedge-seats formed in the mating jaw members having inclined surfaces opposed to said grooves, and wedges driven into said seats and bearing on the conductors to force the latter into engagement with the teeth.

3. A trolley conductor support comprising complementary jaw members each provided with a longitudinally extending groove adjacent its lower edge, said grooves coacting to clasp the wires when the members are assembled, upwardly extending ears adjacent the ends of the jaw members, the opposed ears of the jaw members contacting at their upper ends to provide a fulcrum and said ears being provided below the fulcrums with registering holes to receive clamping bolts, and the ears of one jaw member being provided with an integral connecting hanger bar spaced upwardly from the intermediate portion of the jaw member, the axial center of said bar being disposed in the plane of the parting of the coacting grooves, the intermediate portions of the jaw member being cut away to expose the grooves from above, and wedges introduced through the cut away portions and driven into the coacting grooves to bind the wires in place.

4. A trolley conductor splicer comprising complementary jaw members each provided with a longitudinally extending groove adjacent its lower edge, said grooves coacting to clasp the wires when the members are assembled, teeth in said grooves, upwardly extending ears adjacent the ends of the jaw members, the opposed ears of the jaw members contacting at their upper ends to provide a fulcrum and said ears being provided below the fulcrums with registering holes to receive clamping bolts, and the ears of one jaw member being provided with an integral connecting hanger bar spaced upwardly from the intermediate portion of the jaw member, the axial center of said bar being disposed in the plane of the parting of the coacting grooves, the intermediate portions of the jaw member being cut away to expose the grooves from above, and wedges introduced through the cut away portions and driven into the coacting grooves to force the wires into engagement with the teeth.

ALBERT H. GENTER.
